ATTORNEY.

UNITED STATES PATENT OFFICE.

WALTER SCOTT CARVER, OF BLOOMFIELD, NEW JERSEY.

DOUBLE ENVELOP.

SPECIFICATION forming part of Letters Patent No. 604,723, dated May 31, 1898.

Application filed August 4, 1897. Serial No. 647,074. (No model.)

To all whom it may concern:

Be it known that I, WALTER SCOTT CARVER, a citizen of the United States, and a resident of Bloomfield, in the county of Essex and State of New Jersey, have invented certain new and useful Improvements in Double Envelops, of which the following is a specification.

This invention relates to a certain new and useful improvement in twin or double envelops, and has for its object the economical production of two envelops from a single sheet of material in which no seams will appear on the front faces and which may be used either together or be readily detached and used separately or be bound with similar envelops between suitable covers to constitute a file.

To these ends therefore my said invention consists in a peculiarly-shaped blank properly folded and in the details of construction, all as hereinafter more particularly described, and pointed out in the claims.

In the accompanying drawings, in the several figures of which like parts are similarly designated, Figure 1 is a plan view of a blank. Fig. 2 is a similar view showing the blank folded over once transversely and with the end flaps or seams in position. Fig. 3 is a back view of the envelop completed. Fig. 4 is a vertical sectional view taken on the line $x-x$, Fig. 3. Fig. 5 is a perspective view of my invention when bound to constitute a file. Figs. 6 and 7 show blank and completed envelops embodying my invention, but of different shape when completed from those shown in Figs. 1 and 3.

The blank I prefer to use is shown in Figs. 1 and 6, and consists of a single sheet of any appropriate material shaped to form the central substantially rectangular portion $a-b$, divided by a transverse fold or crease $c-c$ into two symmetrical and oppositely-disposed halves, each of which is provided with diagonally opposite flaps d and d' , the similarly-arranged gummed end flaps e and e' , and, if desired, with the diagonally opposite notches or cuts f and f' . When it is desired to provide for the separate use of the envelops, a row of perforations $g-g$ is formed along the central longitudinal line of the blank, said perforations being supplanted by a simple

fold or crease when the envelops are designed to be used together. The blank is gummed on both sides of the line $g-g$.

In forming the twin or double envelop from the blank, a fold is made on the line $c-c$, and part a of the blank is folded by revolving it on the line $c-c$ from left to right down upon the face of b . The end flap e is then revolved from right to left and gummed over the part a , and the gummed end flap e is folded over on the part b from left to right, presenting the appearance shown in Fig. 2 and leaving the front faces of the envelops plain and free from seams. The two envelops thus formed are then folded together on the crease or line of perforations $g-g$, presenting the appearance shown in Fig. 3, and producing two envelops joined together at their bottom line, the object of gumming along said line being to separate the pockets of the two envelops, and where perforations are used to permit the envelops to be detached from each other and each remain perfect and intact.

I have illustrated in Fig. 4 a modification of my invention, which consists in interposing near the bottom of each envelop a strip or guard h of suitable material, the function thereof being to spread the faces of each envelop apart and increase its capacity. To constitute a file, any desired number of the double envelops may be bound together at their meeting edges, as by sewing or pasting, on tape, muslin, parchment, &c., or hinged between suitable covers i , as in Fig. 5.

In Figs. 6 and 7 the arrangement and manipulation of the blank are the same as above described, but the dimensions and shape of the resultant envelops are different, being of greater depth than width, whereas the envelops shown in Fig. 2 are of greater width than depth. When desired, my blank may be used as a single large envelop, as in Fig. 2, by omitting the crease or perforations $g-g$ and gum along their line and folding over one of the flaps d or d' to close the bottom, one of the said flaps being in this case gummed in place. While I have shown each of the envelops provided with covering-flaps d and d' , it will be obvious that one or both flaps may be omitted, that one flap may be made larger than the other, that the flap of the outer en-

velop may be made large enough to cover both, and that one or both of said flaps may or may not be gummed. In the several views the gummed portions are indicated by cross-hatching.

What I claim as my invention, and desire to secure by Letters Patent, is—

1. A double envelop composed of a blank formed of a single piece of material and comprising a substantially rectangular portion *a*, *b*, provided with diagonally opposite end flaps *e* and *e'*, and folded upon itself, substantially as described.

2. A double envelop composed of a blank formed of a single piece of material and comprising a substantially rectangular portion *a*, *b* having a central longitudinal row of perforations, and the diagonally opposite end flaps *e* and *e'* and properly folded upon itself, substantially as described.

3. A double envelop composed of a blank formed of a single piece of material and comprising a substantially rectangular portion *a*, *b*, provided with the diagonally opposite end flaps *e* and *e'*, and properly folded upon itself, in combination with spreading strips or

guards *h*, secured between the inner faces of the envelops, substantially as described.

4. A double envelop composed of a blank formed of a single piece of material and comprising a substantially rectangular portion *a*, *b*, having the diagonally opposite end flaps *e*, *e'*, the similarly-disposed notches *f* and *f'*, and flaps *d* and *d'*, folded upon each other, substantially as described.

5. A plurality of double envelops, each composed of a blank formed of a single piece of material and comprising a substantially rectangular portion *a*, *b*, having the diagonally opposite end flaps *e*, *e'*, and each blank properly folded upon itself, to constitute two united envelops; said envelops being bound at their meeting edges between suitable covers, substantially as described.

Signed at New York, in the county of New York and State of New York, this 30th day of July, A. D. 1897.

WALTER SCOTT CARVER.
